Eig. 10.

A technical drawing of a rectangular frame. The top horizontal side is labeled '24' on the left and '(29)' on the right. The left vertical side is labeled '25' at the top and '24' at the bottom. The right vertical side is labeled '25' at the top and '26' at the bottom. The bottom horizontal side is labeled '26' on the left and '26' on the right. A dashed line labeled 'C' extends from the top center down to the bottom center. The top center of the frame is labeled '10'. The bottom center of the frame is labeled '1'. The bottom left corner is labeled '34' and '8'. The bottom right corner is labeled '9' and '8'. The left side of the frame is labeled '2' at the top and '2' at the bottom. The right side of the frame is labeled '2' at the top and '2' at the bottom.

By J. N. Bryant Attorney

UNITED STATES PATENT OFFICE.

ANTON STREDA, OF ORLAND, CALIFORNIA.

STOVE.

Application filed April 12, 1922. Serial No. 551,777.

To all whom it may concern:

Be it known that I, ANTON STREDA, a citizen of the United States, residing at Or-
land, in the county of Glenn and State of
California, have invented certain new and
useful Improvements in Stoves, of which
the following is a specification.

This invention relates to certain new and
useful improvements in stoves, and has par-
ticular reference to stoves of the camp type
especially designed for field use for burning
of wood either for heating or cooking pur-
poses.

One of the objects of the invention has
reference to a novel type of grate which is
removable from the stove and a series of
baffle walls to cause the smoke and heated
air to travel in a tortuous path within the
body of the stove.

20 The invention further embodies in a stove
of the camp type, bracket arms of wire for-
mation secured thereto to provide hangers
for drying articles or wood to be burned.

With the above and other general objects
in view and others that will appear as the
nature of the invention is better understood,
the same consists in the novel construction,
combination and arrangement of the parts
hereinafter more fully described, illustrated
30 in the accompanying drawings, and pointed
out in the appended claim.

In the drawings forming a part of this ap-
plication and in which like designating
characters refer to corresponding parts
35 throughout the several views:

Fig. 1 is a front elevational view of a
camp stove constructed in accordance with
the present invention showing the entrance
door to the fire box and the ash tray, and
40 also the drying racks positioned at each
side thereof,

Fig. 2 is a side elevational view of the
stove, showing by dotted lines, a base sup-
port to prevent the stove legs from sinking
45 into the ground,

Fig. 3 is a top plan view of the stove,
with a portion of the cover broken away
showing the grate within the stove and the
baffle walls,

50 Fig. 4 is a bottom plan view of the stove
showing the drying racks connecting to an-
choring bolts for the stove legs,

Fig. 5 is a longitudinal sectional view

taken on line 5—5 of Fig. 3 showing the
grate supported above the ash pan and the 55
baffle walls,

Fig. 6 is a vertical cross sectional view
taken on line 6—6 of Fig. 5 showing two
of the baffle walls,

Fig. 7 is a perspective view of the grates 60
removed from the stove,

Fig. 8 is a perspective view of one of the
drying racks removed from the stove,

Fig. 9 is a perspective view of one of the
baffle plates, and

Fig. 10 is a perspective view of the other
baffle plate.

Referring more in detail to the accom-
panying drawings, there is illustrated a
stove of the camp type embodying a bottom 70
wall 1 and an oval shaped side wall 2 hav-
ing a front end 3 and a rear end 4. The
rear end 4 is provided with a smoke pipe 5
positioned adjacent the lower end thereof
as shown in Figs. 2 and 5, the smoke out- 75
let pipe 5 being supported by the strap
hanger 6 secured as at 7 to the rear wall 4
of the stove. Supporting feet 8 are anchored
by bolts 9 to the bottom wall 1 of the stove
as shown in Figs. 4 and 5, while the top 80
wall 10 carries a sectional lid covering 11
overlying the fire pot 12.

As shown more clearly in Figs. 3 and 5, a
vertical partition 13 extends transversely of
the interior of the stove, contacting the side 85
walls and bottom wall 1, the upper edge of
the partition 13 terminating at a point
spaced below the top wall 10 to provide a
passage a.

A grate, of the type best illus- 90
trated in Figs. 3, 5 and 7 is arranged with-
in the stove casing intermediate the parti-
tion 13 and the front wall 3, the grate em-
bodying a horizontal plate 14 having grate
bars 15, and carrying at one end thereof a
perpendicular plate extension 16, the op- 95

posite sides of the grate plate 14 being
notched as at 17 for purposes presently to
appear. Supports for the grate embody
angle brackets 18 secured to the side walls
2 of the stove, the vertical legs of the angle 100
brackets being received in the notches 17 of
the grate, while guide arms 19 carried by
the side walls 2 engage the perpendicular
extension 16 for rigidly holding the
grate in its proper position within the stove. 105

As shown in Fig. 5, the front wall 3 of the

stove is provided with a hinged door 20 to permit the placing of fuel upon the grate plate 14.

The ash tray is slidably disposed within the stove casing beneath the grate 14, the same embodying a bottom wall 21, an arm 22 as shown in Fig. 5, to hold the ash tray elevated in position directly beneath the grate, the front wall 2 of the ash tray carrying a handle 23 to permit removal thereof.

A pair of baffle plates is interposed between the partition 13 and the rear wall 4, to cause the products of combustion to travel in a tortuous path in escaping through outlet pipe 5, one of the baffles being shown in Fig. 10 embodying a perpendicular plate 24, perpendicular edge flanges 25 provided upon the lower ends thereof with feet 26, the upper edge 24' of the baffle plate 24 engaging the stove top 10 as shown in Fig. 5 with the feet 26 resting upon the bottom wall 1 of the stove to form a passage *b* below the edge of the baffle plate and the bottom wall 1 of the stove. The other plate has a vertical wall 27 carrying side flanges 28 and a centrally positioned perpendicular extension 29 on the upper edge thereof, the lower edge of the baffle plate 27 resting upon the bottom wall of the stove while the upper edge of the plate extension 29 engages the top wall 10, providing lateral passages *c* at the upper end of the baffle plate 27 as clearly shown in Figs. 6 and 9.

A rack is associated with each side of the stove, one of the racks being shown in detail in Fig. 8 and being constructed of a wire frame embodying side bars 30 having cross bars 31 and angularly extending feet 32 carried by the lower ends of the side bars being provided with offset portions 33 for engagement with the lower edges of the side walls of the stove, while the extreme ends of the seat are bent as at 34 to be secured to the anchoring bolts 9 of the stove legs 8, the

racks when positioned on the stove occupying a perpendicular position extending laterally of the side walls of the stove as shown in Fig. 1.

From the above detailed description of the device it is believed that the construction and operation thereof will at once be apparent, it being noted that brackets may be employed for drying articles of clothing, or for drying wood to be burned in the stove, being inserted through the door opening 20 and upon the grate 14 the smoke and products of combustion traveling in a tortuous path in passing through the outlet pipe 5, passing through the space *a* at the top of the partition 13, the space *b* adjacent the lower edge of the partition or baffle 24, and through the spaces *c* at the upper edge of the baffle plate 27. The ashes received in the tray 21 are removed by shifting the tray outwardly of the front wall 3 of the stove, while the sectional lid 11 permits the supporting of cooking utensils of various sizes.

While there is herein shown the preferred embodiment of my invention it is nevertheless to be understood that various forms, modifications and arrangements of the parts may be made without departing from the spirit and scope of the invention as claimed.

Having thus described the invention, what I claim as new is:

The combination with a camp stove, of drying racks detachably connected to the opposite sides thereof, each rack formed of a wire frame bent to provide a rectangular portion, angularly disposed feet on the lower end of the rack extending beneath the stove, said feet being constructed for intimately engaging the lower edge of the stove for bracing the rack and hooked ends carried by the feet secured to the supporting means for the stove legs.

In testimony whereof I affix my signature.

ANTON STREDA.
